WASHING MACHINE, INCLUDING CONTROL
VALVE

Frank J. Cozzoli, Plainfield, N. J.

Application April 3, 1947, Serial No. 739,220

3 Claims. (Cl. 134—72)

1

The present invention relates to machines for washing ampoules, vials or other small containers and more particularly to valve mechanisms useful in controlling the flow of fluid to the processing jets of the washer.

Valve mechanisms in machines of this character are used to control the flow of water, air, steam, and detergent materials and must, therefore, be constructed and mounted for operation not only with regard to the character of the processing medium that are to be governed in a given machine but also with regard to factors of movement or elongation of the parts incident to temperature variations. This latter problem is of considerable consequence in washing machines having a series of processing stations and wherein the containers to be washed are carried progressively through the several stations and receive successive charges of processing fluid e. g. water (hot or cold), air, steam, etc. Under such conditions each of the valves in the different supply lines is subjected to and operates under conditions different from adjacent valves, and when, as is often the case, the processing method is revised, the valve that previously controlled, for example, air, will control steam. A primary aim of the invention is therefore to render available a valve mechanism capable of satisfactorily controlling the flow of a fluid medium regardless of its chemical or physical properties and characteristics.

A further aim of the invention is the construction of a valve which eliminates completely all need for packing glands or stuffing boxes and one which is for all practical purposes leak proof in its operation.

Still a further objective of the invention is the construction of a valve which has relatively few operating elements and each capable of rugged construction permitting frequent use of the valve for long periods without need for repair.

In attaining the ends in view it is proposed to construct a valve somewhat in the form of a piston and cylinder and to utilize the "rod end" of the piston as a valve stem and to provide lateral and axial ports therein for the passage of the fluid therethrough. The ported stem is, in accordance with this invention, arranged to function as a slide valve and the "head end" of the piston is preferably crowned or beveled on the stem side so as to cooperate with a valve seat formed in one of the end walls of the cylinder. The two series arranged valves thus constituted control the flow of fluid from the cylinder through the valve stem. In the instant

2

embodiment of the invention the valve stem is urged normally toward valve closed position, in which position the crowned head of the piston engages the seat in the end of the cylinder and the lateral ports in the stem are under the walls surrounding the casing where the stem passes through. The fluid to be controlled by the series valves is caused to enter the chamber containing the headed end of the valve stem and the pressure thereof acting upon the end of the valve stem assists in keeping the valve closed. The valve is opened by moving the valve stem inwardly relative to the cylinder, which movement lifts the crowned head end off its seat and brings the lateral ports in the stem out from under the cylinder wall and into the pressure chamber. Fluid under pressure may then flow past the head end of the valve stem, through the lateral ports into the axial port in the stem and out the open end thereof.

In the instant adaptation of the valve, the stem of the valve is caused to engage with a seat formed in ampoule carrying tray of the washing machine and the processing fluid discharging therethrough is utilized in cleansing the containers carried thereby. In the preferred form of valve mechanism herein disclosed, the valve casing and the valve stem are arranged for bodily movement together whereby to bring the stem end of the valve successively in engagement with the seats in the respective container carriers as they dwell at the washing stations. After the coupling is made, translatory movement of the valve stem stops and the continuing forward movement of the valve casing effects an opening of the valve to a flow of fluid therethrough. So long as the casing and stem remain shifted as explained, the processing fluid discharges therethrough and through the various washing jets and effects the cleansing operation. At the completion of the operation, the valve casing is withdrawn, which movement first closes the valves, and the continued retracting movement withdraws the stem from the seat in the carrier, and a succeeding indexing movement of the carrier may follow.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been

annexed as a part of this disclosure and, in such drawings, like characters of reference denote corresponding parts throughout all the views, of which—

Figure 1 is a sectional view of a valve constructed in accordance with this invention.

Fig. 2 is a view of portions of a washing machine showing the valve in open position and its relation to a container carrier tray.

Fig. 3 is an end elevational view of a group of valves in relation to a series of intermittently movable container carriers.

With reference more particularly to Figs. 2 and 3 of the drawings and the parts of the washing machine illustrated, it is to be understood that such disclosed portions do not constitute the entire washing machine but only so much of the machine as will give one an understanding of how the valve of this invention is constructed and functions. For a more complete disclosure of a washing machine reference may be had to my prior Patents #2,381,436, #2,417,633, and #2,417,634. For the present purposes it is believed sufficient to explain that the washing machine comprises a series of container carriers 10 that are securely fastened to two bands of links 11. The bands of links form endless chains that track spaced sprocket wheels 12 located at each end of the machine. The distance intervening the axes of the sprocket wheels afford upper and lower horizontal runs (only the upper run is shown in Fig. 3) for the carriers 10, and it is on the upper horizontal run of the machine that the processing of the containers is caused to occur. In the fragmentary view Fig. 2, side tracks 13 and 14 are illustrated which support the container carriers and maintain them in alignment as they progress intermittently from station to station. The side tracks 13 and 14 are secured at their respective ends to sprocket wheel bearing members 15 (only one shown) which in turn are firmly fastened to side frame members 16 (but one shown). The term "station," as herein used, refers to one processing cycle of which but four are represented in Fig. 3. In normal operation, however, the respective carriers are successively indexed through the various stations, with adequate dwell period afforded at each station in which to effect the processing operation. The carrier indexing mechanism may be of the character disclosed in my aforesaid patents or equivalent mechanism, and in the interests of clarity is not repeated herein.

As illustrated in the drawings hereof, each of the container carriers 10 is provided with a series of tubular jets or supports 17 over which the containers a to be washed are placed. The lower ends of the supports communicate with an open-ended conduit 18 formed in the base of the carrier. The open end 19 of the conduit 18 is conically recessed and forms the female portion of a separable coupling later to be described.

The control valves of the present invention are indicated generally at 20. These valves control the flow of the process fluids to the jets and also form the male portions of the couplings to which reference was just made. In the present machine the valves are arranged coaxially with the conical seats 19 of the container carriers. Fig. 1 illustrates in cross-section the construction of the improved valve, which includes a casing 21, a headed valve plunger 22, a cap member 23 and a compression spring 24 that operates between the cap and the headed end of the valve stem. The valve casing is formed with a pressure cham-

ber 21a which is capped at one end by the cap 23, and provided at its other end with a valve seat 21b, preferably tapered. The valve seat merges into a smaller diameter reamed bore 21c. The valve member 22, is formed with a head end 22a, that is smaller in diameter than the pressure chamber, and a stem portion 22b, the latter being formed closely but slidably to fit the reamed bore 21c in the casing. The head end 22a of the piston operates in the enlarged chamber 21a of the casing and preferably is given a somewhat spherical shape on the side 22c facing the stem portion. The shaped end 22c normally seats against the valve seat 21b in the casing and forms therewith a ring seal. If desired, the head end may be conically shaped, flattened or otherwise contoured and the seat 21b complementally shaped to act as a valve.

The stem portion 22b of the valve plunger is formed with a central conduit 22d leading from its outer end to a point adjacent the head portion, where one or more cross ports 22e extend from the axial conduit to the surface of the stem. The position of the crossports axially of the stem is preferably such that when the valve stem is extended its maximum distance, the cross ports 22e are completely bridged by the surrounding wall of the bore 21c in the casing, and when the valve stem is retracted (valve open position illustrated in Figs. 1 and 2) the cross ports 22e are in open communication with the chamber 21a. In the latter position, fluid lead into the chamber 21a is free to pass around the head end of the valve plunger, past the seat 22c—21b, through cross ports 22e, and out the axial port 22d to the point of use.

In the present embodiment, the forward end of the valve plunger 22 is adapted to be coupled periodically to the respective container carriers 40 as the latter are moved intermittently from station to station, and to that end, the extreme outer end of the plunger is rounded off, as at 22f, in a manner effective to seat in the conical recesses 19 of the respective carriers. When the 45 valve plunger is firmly seated as illustrated in Figs. 1 and 2, a fluid tight connection is formed between the valve and an associated carrier and the fluid passing the valve is caused to enter the conduit 18 and be discharged through the 50 supports 17 to the interiors of the containers carried thereby.

The coupling so formed, is maintained by virtue of the presence of the compression spring 24 interposed between the head end 22a of the valve 55 plunger and the cap 23, which spring is tensioned to urge the plunger always outwardly relative to the casing. Processing fluid is caused to enter the chamber 21a through a conduit 25 that is threaded at one end into the cap 23. The 60 other end of the conduit 25 is connected with a semi-rigid tube 26 that is connected to a supply source of processing medium.

Fig. 2 of the drawings illustrates the relation of the valve as a whole to one of the carriers 65 at one of the processing stations. A valve guide and supporting bar 27, secured to the machine structure, is provided to maintain that relation. The bar 27 is formed with a series of recesses 28, each of which is slightly larger than the external diameter of the valve casing 21. The control valves move axially within the recesses and the extra clearances provided, allows for a slight sideways float of the valves whereby a good seal is obtained between the valve plungers 70 and container carriers notwithstanding slight

irregularities or inevitable elongation and contraction of the machine elements incident to variations in temperature.

Any suitable means may be provided to effect actuation of the valve, but in the present instance it is preferred to actuate the valves in unison by a series of bifurcated levers 30 that are arranged to straddle the respective conduits 25 and bear against the valve caps 23. The levers 30 are locked upon a rock shaft 31 that is journaled in bearings 32 provided by the machine frame. Medially of the various actuating levers, a follower lever 33 is secured, which lever 33 carries a roller 34 at its outer end. The roller 34 rests atop a slide bar 35 that is guided in a bearing block 36 also supported by the machine frame. The lower end of the slide bar 35 carries a roller 37 arranged to track a cam 38 mounted upon a continuously rotating cam shaft 39. The cam 38 is contoured to raise and lower the slide bar in timed relation with the dwell periods of the container carriers, as will be understood, so that after the carriers come to rest the valves will move inwardly bodily toward the carriers and establish a fluid connection with the carrier conduits 18, and thereafter the continued movement of the casing in a plunger overtaking direction effects an opening of the valve at the zones 21b and 22e thereof. The reverse movement of the valve is accomplished preferably by one or more tension springs 40 that are connected between the main frame and the free ends of supplementary levers 41 secured upon the rock shaft 31. The levers 30 and 33 and 41 are arranged at approximately right angles so that upward and downward movement of the levers 33 and 41 affect a shifting of the valves 20 horizontally. To effect the withdrawing of the valves, each supply conduit 25 is provided with a collar member 42 against which the opposite sides of the levers 30 react when the low portion 38b of the cam 38 arrives under the slide bar 35. During normal operation, the valves move in and out in synchronism with the machine movements, and the semi-rigid process tubes 26 flex slightly during such operations.

The operation of one of the valves is as follows: a container carrier is moved into position aligned with the valve (see Fig. 3) and after coming to rest in that position, the valve assembly is bodily advanced until the end of the plunger 22 is seated in the cone 19 of the associated carrier. Thereafter a further advancing movement of the casing 21 causes relative endwise movement to occur between the valve plunger and its casing and an opening of the valve at the zones 22c and 22e is brought about. Processing fluid from the line 26 is thus caused to pass through the assembly and to be injected into the interiors of the containers, as previously described. After the elapse of a given period of washing, the continued rotation of the main cam shaft 39, allows the slide 35 to drop and the rock shaft 31 is oscillated in the reverse direction and the valve assembly is withdrawn. The initial withdrawing action effects first a closing of the valve at the two zones 22c and 22e and then an uncoupling of the valve stem from its seat in the container carrier. The spring 24 in each valve, augmented by the supply fluid pressure, effects the valve closing with the result that the process fluids are cut off and stopped before uncoupling occurs. All of the valve assemblies, it will be understood, perform in a similar manner.

The cam action of the instant embodiment

of the invention is such that the valve stems are completely withdrawn from their seats in the respective carriers and move slightly away therefrom before the carriers are advanced, in the direction of the arrow Fig. 3, to the next station. As many control valves are provided as there are washing stations, and each may control a different processing fluid as the nature and sequence of steps in the washing method may prescribe, and the valves constructed as disclosed herein, together with their somewhat free floating mounting have been found well adapted to control a wide range of agents and effectively to couple and uncouple and to start and to seal off the flow sequentially in a leakless manner. Moreover, with the valve of the present invention, the pressure exerted in causing the valve to "open" reacts through the spring in the pressure chamber and in consequence sturdy actuating mechanism may be employed without danger of producing a harmful overtravel of the coupling end of the valve into the seat in the container carrier. Such a valve, it will be seen is self compensating in an axial direction as well as laterally whereby repeated couplings to the container carriers may be effected regardless of minor variations or irregularities, however caused, in their positioning. Also, it is to be noted that the pressure required to effect the coupling and the opening of the valve during the dwell period of the carriers is borne by the carriers and not by the containers, which makes it possible to employ strong springs and obtain tight shut offs during carrier index movements without resort to packing materials and without danger of container fracture as would be the case with a valve designed to operate against the containers directly.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims.

Having thus revealed this invention, I claim as new and desire to secure the following combinations and elements or equivalents thereof, by Letters Patent of the United States:

1. In combination with a washing machine adapted to wash containers supported upon carriers movable intermittently and successively through a washing station and in which each of the carriers is provided with a manifold for processing liquid and processing nozzles in communication with the manifold, a reciprocable control valve assembly at the washing station adjacent the carriers and normally positioned out of the path of movement of the carriers, said assembly comprising a casing member mounted for bodily reciprocatory movement selectively into and out of the path of movement of the carriers and a valve element carried by the reciprocatory casing and as to which the casing is constructed and arranged for movement also relatively thereto, and said valve element having a hollow stem portion projecting from the casing and a head portion within the casing adapted on movement of the casing relative to the valve element to perform a valving function, and power means operatively engaging the valve casing operable

during a period of dwell of the carriers to shift the said casing of the valve and its said stem portion bodily toward the carrier to effect an abutting engagement of the hollow stem portion of the valve element with the manifold in a selected carrier and to shift the valve casing alone a further distance in an overtaking direction on the valve stem element to effect an opening of the valve to fluid flow through the valve stem to the manifold of the carrier, means operative to shift the casing of the valve in the opposite direction on the stem element whereby to close the valve and thereafter to move the casing and the valve element bodily away from the carrier to effect a disconnection and to permit the cyclically movable carrier to pass, and relatively stationary guide means associated with the valve assembly for maintaining the assembly in substantial coaxial alignment with the manifold in a related carrier when the latter is at rest at the washing station.

2. In combination with a washing machine adapted to wash containers supported upon carriers moveable intermittently and successively from one washing station to another and in which each of the carriers is provided with a manifold for processing liquid and processing nozzles in communication with the manifold, a reciprocable control valve assembly at each of the washing stations adjacent the carriers and normally positioned out of the path of movement of the carriers, each assembly comprising a casing member mounted for bodily reciprocatory movement selectively into and out of the path of movement of the carriers, a valve element carried by each of the reciprocatory casings and as to which the respective casing is adapted for movement relatively thereto, and said valve element having a hollow stem portion projecting from the casing and a head portion within the casing adapted on movement of the casing relative to the stem to function as a valve, and power operated means

operatively engaging the valve casings operable during a period of dwell of the carriers to shift the said casings and their respective stem portions bodily toward the carriers to effect an abutting engagement of the hollow stem portions of the valve elements with the manifolds of associated carriers and to shift the valve casings alone a further distance in an overtaking direction on their valve stems elements to effect an opening of the valves to fluid flow through the valve stems to the manifolds of the carriers, means operative to shift the casings of the valves in the opposite direction whereby to close the valves and thereafter to shift the casings and the valve elements bodily away from the carriers to effect disconnection and to permit the cyclically movable carriers to pass to the next station, and relatively stationary guide means associated with each valve for independently maintaining the respective valve assemblies in substantial coaxial alignment with the manifolds of the related carriers when the latter are at rest at the washing stations.

3. The combination of claim 2 in which the relatively stationary guide means associated with the respective valve assemblies provides for limited lateral float of each valve assembly to render the latter self-aligning during the movement of the respective assemblies into operative position in relation to the carriers.
